UNITED STATES PATENT OFFICE.

ALBERT W. BUEHLER, OF TOLEDO, OHIO, ASSIGNOR TO THE TOLEDO BUTTON MACHINE COMPANY, OF TOLEDO, OHIO, A CORPORATION OF OHIO.

SHOE-BUTTON-FASTENING MACHINE.

1,244,466.

Specification of Letters Patent.

Patented Oct. 30, 1917

Application filed August 5, 1916. Serial No. 113,309.

To all whom it may concern:

Be it known that I, ALBERT W. BUEHLER, a citizen of the United States, and a resident of Toledo, in the county of Lucas and State 5 of Ohio, have invented a certain new and useful Shoe-Button-Fastening Machine; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates particularly to shoe button fastening machines and has for its object the provision, in association with the button feed mechanism of such machines, of simple and efficient means for serving both 20 to clamp the button feed tube in operative position and to stop the feed of buttons from the hopper to the tube when desired.

The invention is fully described in the following specification, and while, in its 25 broader aspect, it is capable of embodiment in numerous forms, a preferred embodiment thereof is illustrated in the accompanying drawings, in which,—

Figure 1 is a perspective view of a portion 30 of the button feed mechanism of a shoe button fastening machine with the feature embodying the invention associated therewith and in button tube clamping position. Fig. 2 is a similar view with the feature embodying the invention in button feed stopping position, and Fig. 3 is a top plan view 35 of Fig. 1.

Referring to the drawings, 1 designates an upright frame part to the rear edge of 40 which is secured a hopper 2 for containing buttons to be fed to the button setting parts of the associated machine. A vertically movable slide 3 operates in the hopper to raise buttons to an inclined feed-way 4 provided in the upper forward portion of the hopper and registering at its forward end with an inclined feed-way 5 provided in the top of the frame part 1. The feed-ways 4 and 5 comprise endwise communicating 45 grooves of suitable size to receive the button eyes, as is well understood in the art.

The top-plate 6 is disposed above portions of the feed-ways 4 and 5, being secured to the hopper, as at 7, and rigidly supported 55 at one side of its forward end above the

frame part 1 by a screw 8 and spacing post or sleeve 9. The rear end of the plate 6 is tapered to direct transversely from the feed-way 4 buttons the eyes of which are not properly positioned in the feed-way for feeding down the same.

10 designates the customary button tube which registers at its rear end with the feed-way 5 and extends downward on an incline therefrom, whereby buttons may feed by gravity down the feed-ways 4 and 5 and into and down the tube to the button setting mechanism.

A headed pin 11 rises from the forward end portion of the top plate 6 and pivoted 70 at its rear end to this pin for transverse swinging movements relative to the frame part 1 is a button-tube clamping finger 12. When this finger is disposed in parallel relation to the path of feed of the buttons its 75 forward end engages over the rear end of the button tube 10 and holds it in operative position, as shown in Figs. 1 and 3. The forward end of the clamping finger is shaped to seat over the tube. A coiled compression spring 13 encircles the pin 11 intermediate the pin head and the finger 12 and serves to yieldingly retain the finger 12 in any position of its adjustment.

A tongue 14 projects outward and downward from one side edge of the finger 12 adjacent to its rear end and when the finger is swung to one side in the tube releasing position, shown in Fig. 2, said tongue stands in position to obstruct and stop the feed of 80 buttons from the hopper down the feed-ways 4 and 5 to the tube 10.

It is evident that when buttons are not wanted from the hopper the clamping finger 12 may be quickly turned to one side thus 85 stopping the flow of buttons to the feed tube and providing abundant space for feeding buttons to the tube by hand, and since all sizes and shapes of buttons are fed into one tube it eliminates the necessity of providing extra devices for such purpose. It is also evident that when buttons from the hopper are stopped by the tongue 14 there is an accumulation of buttons in the feed-way at the rear of said tongue and these buttons immediately flow into the tube upon a return of the clamping finger to its tube holding position.

I wish it understood that my invention is 90 not limited to any specific construction, an 110

angement or form of the parts as it is capable of numerous modifications without departing from the spirit of the claims.

Having thus described my invention, what I claim as new, and desire to secure by Letters Patent, is,—

1. In a shoe button fastening machine, means forming a button feed-way, a member pivotally carried by said means and having an arm which extends longitudinally of the feed-way when the member is in one position and is pivotally movable laterally of the feed-way from such position, and an arm which stands in obstructing relation to the feed buttons down the way when the member is in another position.
2. In a shoe button fastening machine, a button feed-way, a button feed tube leading from said way, and a member mounted for horizontal swinging movements and operable when in one position to hold said tube and when in another position to interrupt the feed of buttons to said tube.
3. In a shoe button fastening machine, a button feed-way, a button feed tube leading

from said way, and a finger pivoted over said way for horizontal swinging movements, said finger being operable when in one position to close the top of said way to said tube and to engage and clamp the tube in position and having a tongue which moves into position to obstruct the feed of buttons down said way when the finger has been swung from tube clamping position.

4. In a shoe button fastening machine, a button feed-way, a button feed tube leading from said way, a finger pivoted over said way for horizontal swinging movements and yielding movements longitudinally of its pivot, said finger being operable when in one position to close the top of said way to said tube and to engage and clamp the tube in position, and a tongue which moves into position to obstruct the feed of buttons down said way when the finger is swung from tube clamping position.

In testimony whereof, I have hereunto signed my name to this specification.

ALBERT W. BUEHLER.
